(57) **CLAIM**

We claim the ornamental design for a planer, as shown and described.

DESCRIPTION

FIG. 1 is a top perspective view of a planer of the present invention;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a right side view of the planer of FIG. 7, wherein the collection bag is removed.

Any broken lines in the drawings are for illustrative purposes only and form no part of the claimed design.
